RADAR ANTENNA LOBING POWER-DIVIDER

Francis A. Marasco and Edwin S. Oxner, Indianapolis, Ind., assignors to the United States of America as represented by the Secretary of the Navy

Application August 18, 1952, Serial No. 305,096

3 Claims. (Cl. 343—5)

(Granted under Title 35, U. S. Code (1952), sec. 266)

The invention described herein may be manufactured and used by or for the Government of the United States of America for governmental purposes without the payment of any royalties thereon or therefor.

The present invention relates generally to radar tracking antennas, and more particularly to a lobing, power-dividing wave-guide therefor, adapted to simultaneously transmit, and sequentially receive, pulses.

Prior art devices of this type achieved lobing by either a mechanical switching between two antennas or, when only a single antenna is used, by shifting the phase of one-half of the antenna with respect to the other to produce a double lobed pattern of radiation. This phasing may be accomplished electromechanically or electronically. The mechanical switching system is simple in operation and trouble free, but it is inefficient in the use of equipment and space since it requires two antennas. The electro-mechanical phasing system is more efficient than the mechanical system in its utilization of equipment and space, but is subject to the disadvantages that any instability introduced into the phasing mechanism by mechanical imperfection would appear as distortions in the received image. The electronically switched phasing system has the disadvantage of introducing additional complex electrical circuits into an already complex mechanism thereby increasing the possibility of fault and the difficulty of maintenance. All of these prior art lobing systems have the limitation that the lobe switching occurs both on the transmission and receiving cycle.

It is therefore the principal object of this invention to provide a lobe switching system which permits the transmission of a single lobe while switching the lobes for reception.

A second object of the invention is to provide simplified mechanical means to switch the lobes.

A third object is to provide for neutralizing the lobe switching while transmitting, thereby permitting no reflection of transmitted power to occur.

A fourth object of this invention is to provide a wave-guide power-divider in which maximum attenuation is possible in one of two divisions when the other division is conducting.

A fifth object of the invention is to provide a wave-guide power-divider structure which produces negligible reflected waves in the system.

Other objects and many of the attendant advantages of this invention will be readily appreciated as the same becomes better understood by reference to the following detailed description when considered in connection with the accompanying drawings wherein:

Fig. 1 is a schematic diagram of the device.

Fig. 2 is the perspective view of the power-divider.

Referring now to the drawing where like reference characters designate like or corresponding parts throughout the several views, there is shown in Fig. 1 a diagrammatic representation of a conventional radar system adapted to incorporate the present invention, in which numerals 11 and 12 designate two electromagnetic feed horns of the

2

antenna 13 with reflector 14. The horns 11 and 12 are connected to the power-divider of the present invention which is generally designated as 16 and includes a section of rectangular wave-guide 17 designed to operate in the standard $TE_{1,0}$ mode or $TE_{n,0}$ mode, in which TE refers to the transverse electric field and the first subscript refers to the number of $\frac{1}{2}$ wave-length patterns along the long side of the wave-guide, and the second subscript refers to the number of $\frac{1}{2}$ wave-length patterns along the short side of the wave-guide, n being any whole number, and said section 17 having a conducting partition 18 which equally divides the section of the wave-guide in the axial direction and which is perpendicular to the direction of the transverse electrical field, as can be more clearly seen in Fig. 2, thereby forming two wave-guide channels 19 and 21. Since this partition divides the narrow side of the wave-guide it does not affect the wave-length response of the guide, but the electrical field strength will be divided according to the relation

$$\frac{V_1}{V_2} = \frac{b_1}{b_2}$$

where V_1 is the field strength across the divided section having an end width of b_1 , and V_2 is field strength across the other section which has a width of b_2 where $V_1 + V_2 =$ the total field strength before division and $b_1 + b_2 =$ the total width of the wave-guide in the direction perpendicular to the transverse magnetic field. The power-divider 16 is connected at one end by means of a choke or cover joint 22 of standard construction to a feed line wave-guide 23 which connects to the transmitting and receiving circuits indicated by box diagram at 24. The other end of the divider 16 is connected to the antenna feed wave-guides 25 and 26, which are of standard size, by an impedance matching section 27 connected to each of the channels 19 and 21 of the power-divider. It has been found desirable to bevel the end of partition 18 at 28 to prevent reflection of the waves entering the power-divider from the transmitter with the attendant establishment of standing waves and the consequent loss in radiated power. To adapt the power-divider for use as a lobe switching or lobing device, there are provided two series of stub sections 29 and 31, one in each of the channels 19 and 21. These stub sections 29 and 31 are attached to TR boxes 32 and 33 containing the usual TR tubes and when so connected are proportioned in length to produce the equivalent of a $\frac{1}{2}$ wave-length shortened stub when the TR tube is fired. It is found that by placing these stub sections in the channels of the divider rather than in the full size wave-guide a much higher degree of attenuation is obtained. The stub sections 29 and 31 are extended beyond the TR box such a distance as to produce a section length of an odd number of $\frac{1}{4}$ wave-length. The outer ends of the stubs are alternately closed with semi-circular rotatable shorting closure plates 34 and 35 which are mounted in opposed and spaced relation on a shaft 36 which is driven by motor 37. Said shaft is also connected to a synchronizing selsyn system 38. Here it has been found desirable to use a choke collar to allow for efficient operation of the closures. The provision of the choke joint permits the semi-circular closing plates to be spaced from the end of the stub section with sufficient clearance for good mechanical operation without appreciable loss in electrical efficiency. There is also provided the usual tracking mechanism, indicated at 39, to position the antenna.

In operation the transmitted impulses from the transmitter enter the power-divider and when it reaches each of the stub sections sufficient power enters the stub to fire the TR tubes producing the equivalent of a short circuit across the entrance to the stub section, since the stub section and the fired TR box are equivalent to a $\frac{1}{2}$

wave-length section, thereby permitting both channels of the power-divider to simultaneously transmit the impulse from the transmitter to the antenna.

When the transmitting pulse is complete the TR tubes cease firing and the stub section becomes an open circuit so long as the end of the stub section is open, but as the semi-circular plates 34 and 35 are rotated they successively close and open the stub sections to produce alternately a short of the stub section, which gives a low impedance in channels of the power-divider, and an open stub section, which gives a high impedance in the channels. When the stub section is shorted by the closing of the open end by the plate that channel of the divider will conduct while the other stub section remains open and the high impedance reflected into the corresponding division of the divider produces a high degree of attenuation while the alternate reception of the reflected signal through the two feed horns produces a lobing effect.

The power-divider described above in connection with radar lobing could obviously be used wherever it was desirable to provide for alternate reception or through two channels, in which case the closing of ends of the stub sections could be accomplished by hand or other suitable mechanical means.

It should be understood, of course, that the foregoing disclosure relates to only a preferred embodiment of the invention and that numerous modifications or alterations may be made therein without departing from the spirit and the scope of the invention.

What is claimed and desired to be protected by Letters Patent of the United States is:

1. In combination with a radar transmitting and receiving system, a power-divider comprising a section of wave-guide of suitable dimension to operate at the desired frequency in the desired mode having longitudinal conducting partition forming two channels of reduced cross-sectional area, two transmit-receiver boxes, means connecting one of said boxes in series with each of said channels, said means comprising a first pair of stub sections which when connected between each of said boxes and its corresponding channel produces a wave-guide section an equivalent half wavelength long, a second pair of stub sections of a wave-guide, one of said second pair connected at one of its ends to each of said transmit-receive boxes to produce with the first stub section and

the transmit-receive box a wave-guide section an equivalent odd quarter wavelength long, means for alternately shunting said second pair of stub sections.

2. In a radar system a power-divider for use with a rectangular wave-guide, said divider being connected between a transmitter-receiver and an antenna, said divider comprising two tubular channels of rectangular cross-section connected in a Y connection to the wave-guide from the transmitter-receiver, each of said tubular channels having one of its cross-sectional dimensions smaller than the corresponding cross-sectional dimension of the wave-guide to which it is connected, a first means for simultaneously rendering the two tubular channels conductive, a second means operative to render said channels alternately conducting when said first means is inoperative, said first means consisting of a TR tube in a TR box connected at right angles to each of the channels by a stub section of a length to produce in series with the TR box the equivalent of a $\frac{1}{2}$ wave-length shorted stub when the TR tube fires, said second means including a stub section extending beyond each of the TR boxes a distance to provide in series with the TR boxes stub sections of an off multiple of $\frac{1}{4}$ wave-lengths when open and being provided with means for sequentially closing and opening the open ends of said stub sections.

3. A device as claimed in claim 2 in which the means for sequentially closing and opening the open ends of the stub sections comprises a rotatable shaft having semi-circular plates mounted in opposed and spaced relation to each other and being mounted adjacent the stub sections so that the semi-circular plates will alternately close and open the open end of the stub sections when the shaft is revolved; a motor connected for rotating said shaft.
